UNITED STATES PATENT OFFICE.

FREDERICK R. MATTESON, OF TAUNTON, MASSACHUSETTS, ASSIGNOR TO FREEMAN-DAUGHADAY COMPANY, OF CHARTLEY, MASSACHUSETTS, A CORPORATION OF MASSACHUSETTS.

SEPARABLE CUFF-BUTTON.

1,352,908.

Specification of Letters Patent. Patented Sept. 14, 1920.

Application filed January 6, 1920. Serial No. 349,681.

To all whom it may concern:

Be it known that I, FREDERICK R. MATTESON, a citizen of the United States, and resident of Taunton, in the county of Bristol and State of Massachusetts, have invented certain new and useful Improvements in Separable Cuff-Buttons, of which the following is a specification.

This invention relates to separable cuff buttons constructed of two parts adapted to be detachably connected together; and the object of this invention is to provide such a cuff button in which each of the two parts is provided with outer and inner flange members connected by a post, one part of the button being provided with a head and the other part with a pair of elongated socket-forming arms which are adapted to receive and releasably retain the head member of the other part between them.

With these and other objects in view, the invention consists of certain novel features of construction, as will be more fully described, and particularly pointed out in the appended claims.

In the accompanying drawings:

Figure 1— is a side elevation showing the two parts of my improved button connected together.

Fig. 2— is a side elevation partly in section illustrating the internal mechanism of the two parts of the button whereby they are separably connected together.

Fig. 3— shows the head member of the button partly in section.

Fig. 4— shows the socket member of the button in section.

Fig. 5— is a detail view in perspective showing the elongated spring arms which yieldably embrace the head of the opposite member to releasably connect the two parts of the button together.

Fig. 6— is a side elevation showing the head gripping arms as bent up into tubular form ready to be inserted into the hollow post of one part of the button; also showing the arms enlarged slightly at a point intermediate the inner and outer ends.

Fig. 7— is an elevation sectioned on line 7-7 of Fig. 6, shown without the enlarging rib or portion.

Fig. 8— is a top view of the gripping arms, showing each as bent into a semi-

circular form to embrace the sides of the head of the other button part.

Fig. 9— is a view showing the enlarged portion of the arms as mounted to engage the side walls of the post in which they are mounted, to influence the tension of their engaging ends.

With reference to the drawing, each of the two opposite button parts has two spaced apart heads or flanges to engage the fabric of the cuff and be retained therein even when the parts of the button are disconnected. These button parts may be constructed in any suitable way, but for convenience I have shown the stud part 10 as provided with a tubular post 11 having a flaring inner end flange 12. A head member 13 is preferably formed from sheet metal having a contracted neck portion 14 and a base flange 15, the edge 16 of which base is rolled over that of the flange 12 on the post. This head is preferably formed with a somewhat pointed end 17 whereby it may more readily enter the socket member in the other part of the button.

This socket part of the button is provided with an outer flange or head portion 18 and an inner flange or head portion 19, which flanges are connected by a tubular post 20.

In this tubular post I have mounted my improved head gripping member 21. This gripping member is preferably formed of sheet stock struck up into the tubular shape illustrated in Fig. 5, having two arms 22 which are connected by a base portion 23, the outer or free ends of these arms being provided with inwardly projecting gripping rib portions 24, and these arms are bent up, as illustrated in Fig. 6, to stand parallel with each other forming two opposing, semi-circular, yieldable gripping members spaced apart at their free ends to receive and releasably retain the head 13 of the opposite part or member, between them.

In assembling the parts these arms are positioned within the tubular portion 20 of the button, the base plate 23 extending laterally across the end of this tubular member and when the outer plate 25 is rolled or secured in position, it serves to bond or lock this base plate 23 in position to securely hold the same in the tubular post.

My improved separable button is simple

and inexpensive in construction and is most effective in its operation in that with the greatly elongated spring arms 22, the gripping member serves to readily yield to receive the head 13 of the opposite button part, and the inwardly projecting circular rib portion 24 in engaging the neck portion 14 of the head member, serves to hold the two button parts securely together and prevents accidental separation thereof.

By the construction of my two-part button, each part is retained in the fabric of the cuff when the parts of the button are disconnected.

It is found to be of advantage to support the gripping arms by the walls of the post at a point intermediate their opposite or inner and outer ends so as to stiffen their opening action; one way being that of enlarging or pressing outwardly a portion of the arms as shown at 26 in Figs. 6 and 9, to engage the walls of the post at the desired point, leaving the open ends free to expand. Instead of enlarging the arms the walls of the post may be contracted slightly at this point if desired or any other suitable means may be employed for supporting these arms to control their engaging tension.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. A separable cuff button formed in two parts each having an inner and an outer flange member connected by a post, one part being provided with an engaging head portion, the other part having a pair of elongated opposing yieldable arms mounted within its post and spaced apart at their free ends to receive and releasably retain the said head of the other part between them.

2. A separable cuff button formed in two parts, each having an inner and an outer flange member connected by a post one part being provided with an engaging head portion, the other part having a pair of elongated opposing yieldable arms mounted

within its post and spaced apart at their free ends to receive and releasably retain the said head of the other part between them, the opposite ends of said arms being connected together and retained in the outer flange portion of its part.

3. A separable cuff button formed in two parts, each having an inner and an outer flange member connected by a post, one part being provided with an engaging head portion, the other part having a pair of elongated opposing yieldable arms formed of one piece of sheet metal struck up into substantially tubular form folded upon itself and mounted within its post, the free ends of said arms being spaced apart and provided with an inturned portion to receive and releasably engage the said head of the other part.

4. A separable cuff button formed in two parts, each having an inner and an outer flange member connected by a post, one part being provided with an engaging head portion, the other part having a pair of elongated opposing yieldable arms formed of one piece of sheet metal struck up into substantially tubular form folded upon itself and mounted within its post, the free ends of said arms being spaced apart and provided with an inturned portion to receive and releasably engage the said head of the other part, and said arms at the fold being provided with a lateral extension by which it is retained in the outer flange portion of its part.

5. A separable cuff button formed in two parts each having an inner and an outer flange member connected by a post, one part being provided with an engaging head portion, the other part having a pair of elongated opposing yieldable arms mounted within its post and spaced apart at their free ends to receive and releasably retain the said head of the other part between them, and means whereby said post is caused to support said arms at a point intermediate its opposite ends to control their opening action.

In testimony whereof I affix my signature.

FREDERICK R. MATTESON.
